UNITED STATES PATENT OFFICE.

GEORGE E. HOYT, OF SAN FRANCISCO, CALIFORNIA.

REAR-COMPRESSION GAS-ENGINE.

SPECIFICATION forming part of Letters Patent No. 657,934, dated September 18, 1900.

Application filed March 9, 1900. Serial No. 8,033. (No model.)

To all whom it may concern:

Be it known that I, GEORGE E. HOYT, a citizen of the United States, residing at San Francisco, county of San Francisco, and State of California, have invented certain new and useful Improvements in Gas-Engines; and I hereby declare the following to be a full, clear, and exact description of the same, reference being had to the accompanying drawings, forming a part of this specification.

My invention relates to certain improvements in gas motive engines of the type known as "two cycle," in which the piston receives an impulse at each alternate stroke thereof, and to a peculiar construction of such engines that permits successfully operating in this manner.

My improvement consists in a working piston of trunk form, its exterior performing the usual functions of compressing the charges and receiving the pressure of the exploded gas and its interior performing the office of partially compressing the charges—in other words, consists in a moving main trunk-piston and a second stationary piston therein, so the main piston acts each way on all strokes, thus dispensing with a second cylinder and piston to compress the charges, also dispensing with a piston-rod, guides, packing-glands, and various details heretofore employed in engines of this type.

My invention also consists in the construction and arrangement of parts hereinafter more particularly described, and illustrated in the drawings that form a part of this specification, in which—

Figure I is a plan view showing a gas-engine constructed according to my invention. Fig. II is a side elevation, mainly in section; 40 and Fig. III, a horizontal section on the line $\alpha\alpha$ in Fig. II.

The main objects of my invention are to attain with a single piston the functions usually accomplished by two, to secure double the usual amount of bearing-surface for the operating-piston to withstand the wear caused by lateral thrust of the connecting-rod, to remove the inner bearing of the connecting-rod from the highly-heated portion of the engine and permit successful lubrication, and to attain complete simplicity of construction and omission of many of the customary details.

To these ends I construct gas-engines as shown in the drawings now to be referred to, 1 being the main frame of the engine, cast integrally with the cylinder 2. The operating-piston 3 is connected to the crank-shaft 4 by a forked connecting-rod 5 in the usual manner, the inner or piston bearings 6 of the connecting-rod 5 being at the ends of the long cross-pin 7, as seen in Figs. I and II.

8 is a stationary trunk or piston fastened at its outer end to the main frame at 9, as shown in Fig. II, and is slotted at 20 to provide a free path for the cross-pin 7. This trunk 8 fits within the operating-piston 3, completely filling the same at 12 and whole length on the top and bottom at 10 and 11. This, as will be seen, converts the two pistons 3 and 8 into a pump, the chamber 18 representing a pump-barrel or displacement-chamber. The sides of the stationary trunk 8 are cut away, because not required for wear and to admit the bosses 14, that receive the cross-pin 7.

15 is the induction-pipe for air and gas, 75 and 16 a waste-pipe for the burned gases.

The usual spaces for cooling water (marked a) are provided around the combustion-chambers 17 and main cylinder 2.

The operation of the engine is as follows: 80 On the inward or forward stroke of the operating-piston 3 the chamber 18 therein fills with gas and air drawn in through the pipe 15, the passage 19, and valve 21, the piston 3 at the same time compressing a charge that 85 had been previously supplied in the combustion-chamber 17. When the piston 3 has reached the end of its inward stroke and the charge is fully compressed, it is exploded by any of the usual igniting devices attached at 90 22 or some other point within the combustion-chambers 17. When the operating-piston 3 receives the force of the exploded charge, it is driven outward until it passes and opens the exhaust-port 23 and the burned charge escapes down to atmospheric pressure. In the meantime a charge of gas and air in the chamber 18 is expelled, passes through the valve 24, the passage 25, the pipe 26, and the check-valve 27, entering the combustion-chambers 100 17 tangentially and with some force, sweeping out the remainder of the burned gases. This entrance of the air and gas tangentially into the combustion-chamber 17 tends to com-

pletely scavenger or clear out the burned gases therein, first passing around the walls and driving the burned gases to the converging outlet 28, from where they expand and sweep out the whole interior of the main cylinder 2, the respective volume or capacity of the chambers 17 and 18 being so arranged as to cause the proper displacement of the burned gases. This scavenging operation is promoted by the throat at 28 and conical end 29 of the forward end of the piston 3 and is so timed or adjusted that the exhaust-port 23 will be closed just when the fresh charge reaches that point and no fresh fuel escapes. This constitutes the working cycle completed at each revolution of the crank-shaft 4, as will be understood.

Having thus explained the nature and objects of my invention and the manner of its application, what I claim as new, and desire to secure by Letters Patent, is—

1. In a gas-engine, a main cylinder, a trunk-piston movable within said main cylinder, forming a combustion-chamber at the outer end of the latter, a fixed trunk-piston extending within said movable trunk-piston, forming a compression-chamber between it and the latter, a gas inlet and outlet in said fixed trunk-piston, and valves in said fixed trunk-piston, leading to and from said compression-chamber, substantially as specified.

2. In a gas-engine, a main cylinder, a trunk-piston movable therein, forming a combustion-chamber between the two, a fixed trunk-piston extending within said movable piston, forming a compression-chamber between the two latter, a horizontal partition in said fixed trunk-piston, dividing it internally into two chambers or passages, an inlet-pipe for gas to one chamber, an outlet-pipe for gas from the other chamber to the combustion-chamber, and valves between the said chambers or passages respectively and the compression-chamber, substantially as specified.

3. In a gas-engine, a main cylinder, a trunk-piston movable therein, forming a combustion-chamber between the two, an extension 17 to said combustion-chamber in which ignition takes place, a fixed trunk-piston extending within the movable piston forming a compression-chamber between the two latter, said fixed piston being divided into two chambers or passages, a gas-inlet to one passage 19, a

gas-outlet from the other passage 25, to the combustion-chamber, a valve opening from passage 19 to the compression-chamber, and a valve opening into passage 25 from the compression-chamber, substantially as specified.

4. In a gas-engine, a main cylinder, a trunk-piston movable therein, a fixed trunk-piston extending within and guiding the movable trunk-piston, a horizontal partition in said fixed trunk-piston, dividing it internally into two passages, a slotted way in said partition for the cross-pin to traverse in, a cross-pin in said slot fixed in the walls of the movable trunk-piston, a forked connection between said cross-pin and the main crank-shaft, and a main crank-shaft from which the movable trunk-piston derives its motion, substantially as specified.

5. In a gas-engine, a main cylinder, conically formed at its outer extremity, an extension 17 to said main cylinder, opening into the conically-formed end thereof by a contracted passage 28, a trunk-piston movable within said main cylinder, conically formed at its extremity to fit the form of the main cylinder, a fixed trunk-piston extending within and supporting the movable piston, divided into two passages, a gas-inlet to one passage, a gas-outlet from the other passage connected by pipe connection with the said extension 17, and valves between the said passages respectively and the space between the fixed piston and the movable piston, substantially as specified.

6. In a gas-engine, a main cylinder, a trunk-piston movable therein, a fixed trunk-piston extending within said movable piston, supporting and guiding the latter at top and bottom, said fixed piston being flattened at the sides to form clearance-spaces for the strengthening-bosses of the movable piston, bosses 14 formed on the interior of said movable piston, and a cross-pin 7, fixed in said bosses, to form a means of attachment for the mechanism which moves the movable piston, substantially as specified.

In testimony whereof I have signed my name to this specification in the presence of two subscribing witnesses.

GEORGE E. HOYT.
